(57) **CLAIM**

The ornamental design for a intake, as shown and described.

DESCRIPTION

The present application is related to co-dependant U.S. patent application Ser. No. 11/888,119, tiled “Intake,” and filed Jul. 31, 2007.

FIG. 1 is a perspective view of a first embodiment of an intake of our new design;

FIG. 2 is a front side elevational view of the embodiment of FIG. 1 thereof;

FIG. 3 is a rear side elevational view of the embodiment of FIG. 1 thereof;

FIG. 4 is a right side elevational view of the embodiment of FIG. 1 thereof;

FIG. 5 is a left side elevational view of the embodiment of FIG. 1 thereof, FIG. 5 being a mirror image of FIG. 4;

FIG. 6 is a bottom plan view of the embodiment of FIG. 1 thereof; and,

FIG. 7 is a top plan view of the embodiment of FIG. 1 thereof.

The broken line immediately inside the oval features represent a boundary between claimed and unclaimed areas, and form no part of the claimed design. The remainder of the broken lines represent unclaimed portions of the intake, and form no part of the claimed design.
